Patented Aug. 1, 1967

208,206

COMBINED TOWEL AND NAPKIN DISPENSER

Peter L. Helgeson, Macungie, Pa., assignor to Caloric Corporation, Topton, Pa., a corporation of Pennsylvania

Filed July 21, 1966, Ser. No. 3,171

Term of patent 14 years

(Cl. D52—2)

FIG. 1 is a perspective view of a combined towel and napkin dispenser embodying my new design.

FIG. 2 is another perspective view showing the bottom thereof.

FIG. 3 is a front elevational view of the same.

FIG. 4 is a rear elevational view of the same.

I claim:

The original ornamental design for a combined towel and napkin dispenser, as shown.
